WET BLOCKING MACHINE FOR HATS

John Auer, East Norwalk, Conn.

Application May 1, 1939, Serial No. 271,053

9 Claims. (Cl. 223—15)

This invention relates generally to improvements in felt hat blocking machines, and more particularly to a wet blocking machine for felt hats.

It is an object of the invention to provide a machine which shapes the crown and permits shrinking to size, and also shapes and stretches the brim during the wet blocking operation, and therefore securing a better shape and one more nearly like that of the finished hat during the wet blocking, thus doing away with the necessity of the hand blocking operation and securing a better shaped hat and one in better condition for the finishing operations without such hand blocking.

A particular object is to produce a device by which may be secured a better shape around the band and a better fit. Also, to get a better set to the flange-like brim which is not pulled out of shape or stretched when pulled off the block, and to secure these advantages in wet blocking instead of steam blocking.

With the foregoing and other objects in view I have devised a construction as illustrated in the accompanying drawings forming a part of this specification, it being understood however that I am not limited to the specific construction shown and that various changes and modifications may be used within the scope of the invention.

In these drawings:

Fig. 1 is a vertical section through the machine substantially at the center thereof;

Fig. 2 is a side elevation of the machine but with a detail showing of the gripping elements omitted;

Fig. 3 is a top plan view of the lower portion of the device with the block and its support removed, the view being substantially along the line 3—3 of Fig. 2;

Fig. 4 is a top plan view of the upper portion of the device;

Fig. 5 is a detail view showing one portion of the gripping and supporting means, which is the next position after that of Fig. 1;

Fig. 6 is a similar view showing the next position after that of Fig. 5;

Fig. 7 is a detail section of the ring mounting substantially on line 7—7 of Fig. 1;

Fig. 8 is a similar section substantially on line 8—8 of Fig. 1; and

Fig. 9 is a detail section through one side of a modified construction of ring.

The device comprises any suitable frame structure 40 on which the various elements of the

device are mounted. The hat body supporting and gripping means comprises a series of upright levers 11 located within the frame arranged in substantially general oval arrangement corresponding to the general oval shape of the hat to be blocked as indicated in Fig. 3, these levers being pivoted at 12 on arms 13 projecting inwardly from a suitable supporting ring 14 mounted on supporting brackets 15 carried by the frame. At the upper or head ends of these levers is a lower gripping surface or jaw 16 with which cooperates an upper movable gripping jaw 17. This movable jaw is carried by a rod 18 slidable in the head of the lever 11 it being guided on the inner side by a wall 19 below 15 the jaw 16 and on the opposite side by a roller 20. The lever 11 includes an inwardly projecting operating arm 21 in which the lower end of the rod 18 is guided for vertical reciprocating movement by any suitable means such as the rollers 22 on opposite sides of the rod. Any suitable number of these gripping devices are provided around the center of the device to grip the brim 23 of the hat body indicated at 24 these gripping means being placed close together throughout the entire periphery of the brim as indicated in Fig. 3, although for simplicity this figure shows only a portion of these devices.

Associated with each gripping device and mounted on the head thereof is a brim supporting finger 25. This finger is pivoted at 26 to the head of the gripping device, preferably immediately under the stationary jaw 16, and it is mounted to swing from normally horizontal position or slightly upwardly inclined position of Figs. 1 and 5 downwardly to the upright retracted position of Fig. 6. For a purpose presently to be described it is supported in the horizontal or slightly upwardly inclined position and permitted to move to the lower or retracted position by a link 27 pivoted at its upper end to the finger as shown at 28 and pivoted at its opposite end 29 to one arm of the lever 30 pivoted in the upright lever 11 at 31. Pivoted at 32 to the other arm of the lever 30 is an upright connecting rod 33 connected at its opposite end by the means 34 to an operating ring 35, this operating means for all of the fingers 25 being connected to this ring 35 for simultaneous operation. This ring 35 is connected by a link 36 (Fig. 2) to a lever 37 pivoted to the frame at 38 and connected by a link 39 to a hand lever 40 pivoted at 41. It will be seen that pushing down on the lever will raise the supporting fingers 25 to the upper or supporting position of Figs. 1 and 5, but that

lifting up on the lever 40 will move these fingers to the retracted position of Fig. 6.

As shown in Fig. 1 the rods 18 for the clamping jaws 17 are connected by links 42 to a ring 43, and as shown in Fig. 2 this ring is connected by a link 44 to a lever 45 pivoted at 46, and this lever is in turn connected by an adjustable link 47 to a crank 48 on the operating handle 49. Pulling forwardly on this handle 49 will force the ring 43 downwardly to draw the movable jaws 17 down on to a hat brim inserted between these jaws and the stationary jaws 16 to grip the brim.

The free ends of the arms 21 of the levers 11 are rounded as shown at 50 and are seated in a peripheral groove 51 in a head 52 on a sleeve 53 mounted to slide in a bearing 54 carried by a plate 55 mounted in the frame. This sleeve with the head 52 is slidable vertically in the bearing 54, this being accomplished by a lever 56 pivoted at 57 on a link 58 pivoted at 59. The lever 56 is pivotally secured to the sleeve 53 as indicated at 60. The lever 56 is connected by adjustable link 61 with a foot lever 62 pivoted at 63 and having a foot treadle 64. Depression of the treadle 64 will move the sleeve 53 and head 52 upwardly, and through operation of this head on the arms 21 will force the upper ends of levers 11 outwardly, and if at this time the jaws 17 and 16 are clamped on the edge of the hat brim 23 they will tend to pull this brim laterally and may also stretch it somewhat. On release of the treadle 64 the weight of the operating elements, or if this is insufficient additional weights applied thereto, will shift the sleeve 53 and the head 52 downwardly moving the upper ends of the levers 11 inwardly toward the hat brim. Movement of the lever 56 and therefore the connected elements are limited by upper and lower limit stops 65 and 66 which are adjustably mounted on the frame. For instance the stop 65 is adjusted by the hand wheel 67 and then locked in adjusted position by the hand wheel 68. The stop 66 is on a screw 69 and after adjustment may be locked in adjusted position by lock nut 70.

Associated with the clamping and supporting means for the hat brim is a block for shaping the crown and a ring for moving over this crown while on the block to secure the proper shaping and blocking of the hat. This block of proper oval shape is shown at 71 and has a dovetail transverse channel to receive a dovetail rib 72 on a supporting head 73 mounted on a frame 74 by the support 75, the members 73 being secured to the support 75 by any suitable means such as a threaded connection. The member 75 may turn in the frame 74 to properly adjust the block after which it may be clamped by the clamping wheel 76. The block 71 may be clamped on the head 73 by a set screw 77. This permits easy insertion and removal of different sizes of blocks, as in order to change the blocks all that is necessary is to release the set screw 77 and slide the block off the dovetail guide 72 and then a different block of different size or shape may be mounted by merely sliding it on to this guide and setting up a corresponding set screw carried by the block. The block has a central passage 78 and there is also a passage 79 through the support 75 communicating with an air supply pipe 80 for supplying air to the inside of the hat crown to assist in removing it from the block 71, there being an outlet opening 81 at the lower end of the passage 78, the air supply of course being controlled by any suitable

valve mechanism not shown. The block is movable up and down by means of the piston rods 82 on which the frame 74 is supported, these rods passing through suitable guides 83 in the main frame and connected at their lower ends 5 to pistons mounted in the cylinders 84. Hydraulic pressure may be applied to these cylinders through pipes 85 to raise the piston rods 82 and through them the blocks 71. When the pressure is released the weight of the parts will 10 permit the block to move downwardly into the hat body 24 supported by the clamping means. Or if preferred two way pistons may be provided in the cylinders 84 to force the rods 82 in either direction, fluid pressure for operating these cylinders being controlled by any suitable means not shown.

The banding ring for moving over the crown of the hat on the block and shaping the band portion of the crown next to the brim is shown 20 at 86. The operating or smoothing part 87 is somewhat larger than the block 71 so as to move over the crown of the hat embracing the block and smoothing it out against the block. Usually there is a space of about one-sixteenth of an 25 inch between the ring and the block. This ring is mounted on supporting arms 88 to which the ring is secured and these arms are secured at their lower ends as shown at 89 to a supporting block 90 which is provided with a cross-shape 30 recess 91 in its lower side. This recess is adapted to set over a cross-shape head 92 (Figs. 1 and 8) which has a stem 93 seating in the top of a sleeve 94 forming a piston 95 at its lower end. This piston moves in a cylinder 96 carried by suitable 35 brackets 97 and the piston may be operated by hydraulic pressure supplied by a pipe 98 from any suitable control means, not shown. Supplying pressure to the cylinder 96 will raise the piston 95 and the ring 87.

For supplying water to the hat during the blocking operation a pipe 99 is carried by the head 92 or the sleeve 94 through any suitable means such as the supports 100, and this pipe is perforated as indicated at 101 to supply water 45 to the hat for the cooling and blocking operation, the water being supplied to the pipe 99 by any suitable means such for example as a flexible hose connection 102 controlled by any suitable control means.

In Fig. 9 is shown a modified construction of ring 103 to be used in place of the ring 86 if desired. This ring instead of having a substantially plain smoothing portion 87 has a similar portion 104 and at the upper edge of this portion an outwardly extending curved flange 105 to support the brim of the hat and give it the proper curved shape and a similarly shaped setting in the brim.

In operation the levers 11 are brought to the 60 position of Fig. 1 by depressing the foot treadle 64 and the rough hat body 24 is placed with its brim 23 resting on the elevated supporting fingers 25 which are brought to this position by manipulation of the hand lever 40, and with 65 the crown 24 upward. The hat body in this condition is roughly shaped and has not yet been blocked. Immediately the hat is placed in this position the foot treadle 64 is released permitting the head 52 to drop and shifting the upper ends 70 of the levers 11 inwardly so that the free edge of the brim 23 is over the stationary jaws or clamping sections 16 and between these surfaces and the upper jaws 17. Then by manipulation of the lever 49 the jaws 17 are lowered to clamp 75

the edge of the brim between the jaws 17 and the jaws 16 as shown in Fig. 5. As soon as this is done the block 71 is lowered against the crown of the hat body forcing it downwardly and drawing the crown over the block thus moving it to the dotted line position 106 of Fig. 1. Then the ring 86 is moved upwardly over the crown to smooth it against the block. However, before this ring moves upwardly to position the supporting fingers 25 are all dropped to their lower or retracted position as shown in Fig. 6 out of the way of ring 86 by manipulation of the lever 40. The operations are quite rapid so that immediately after the brim is clamped by the clamping jaws 16 and 17 these fingers 25 are moved downwardly out of the way of the ring 87 giving plenty of room for the ring to move over the hat. Also, after the brim is clamped the operator depresses the pedal 64 moving the jaws 16 and 17 outwardly to hold the brim in proper position and give it a certain amount of stretching if desired. The ring 87 is moved up over the crown and up to engage the brim to properly shape the band of the hat, and water from the pipe 99 is sprayed on to the hat to properly cool it. By using the type of ring shown in Fig. 9 the curved flange 105 also shapes the brim giving it the desired transverse curve and setting in the brim. A different size ring 87 is used for each size of block 71, and by the mounting of this ring as shown one ring may be easily and quickly removed and the new ring applied. The supporting block 90 is secured to the head 92 by a set screw 107. Therefore to remove the ring 87 all that is necessary is to release the set screw 107 and remove the ring 87 with its supporting block 90 from the head 92 by merely lifting it off this head. Then another ring with its supporting block may be easily and quickly mounted on the head 92 by the reverse operation. Cross head 92 with a similarly shaped recess in the bottom of the block 90 supports the ring in proper position and prevents its turning. As shown in Fig. 4 the block operating rods 82 are located to the rear of the block and the supporting head or frame 74 projects forwardly from the rods. This leaves the machine clear around the front and sides of the block so that there is nothing to interfere with insertion and removal of the hat body, the blocking operations, etc.

With this device the hat is given a wet blocking by the machine and is stretched and blocked to very nearly the finished shape so that the usual hand blocking operation is eliminated, the hat being sufficiently shaped so that the next operations can be the finishing operations. After the hat is suitably shaped and stretched on the block the ring 87 is lowered and jaws 17 raised to release the hat, and the block 71 moved upwardly with the hat on it, and then by supplying compressed air through the pipe 80 and the passage 78 in the block the hat crown is loosened on the block and is easily removed therefrom without stretching or pulling it out of shape. In old constructions it was difficult to secure the proper support for the hat brim of the roughly shaped body because it was difficult to get the supports to extend inwardly sufficiently on account of the space required for movement of the smoothing ring 87. In the present case, however, as the fingers 25 can be contracted and lowered out of position so as to leave plenty of clearance for movement of the ring 87 these supporting fingers can be extended inwardly far enough to adequately and completely support the hat brim while the clamping jaws

16 and 17 are moved inwardly to positions above and below the brim preparatory to clamping it. Then as soon as the brim is clamped by the jaws 16 and 17 the supporting fingers which are no longer needed for supporting the brim can be quickly lowered out of the way so as not to interfere with the movement of the ring 87.

It will be seen that in the above operation the hat is wet blocked upside down. That is the hat is upside down from the usual hand wet blocking and it is turned inside out. Before blocking with steam the hat has to go through the wet block, that is, it is first blocked in the rough, is stretched, etc. This machine gives the shape and effect of hand blocking. It gives the hand blocked shape and takes the place of hand blocking.

Having thus set forth the nature of my invention, what I claim is:

1. A hat blocking machine comprising a plurality of brim clamps arranged about the hat body and movable toward and from the hat, a brim supporting finger mounted on each clamp and projecting inwardly therefrom, a block movable down into the crown of the hat gripped by said clamps, a banding ring movable upwardly over the crown on the block, said fingers being movable downwardly and outwardly from the brim supporting position, and means for reTRACTING said fingers out of the way of the ring. 30

2. A hat blocking machine comprising a plurality of brim clamps arranged about the hat body and comprising swinging and relatively reciprocable jaw members, brim supporting fingers pivoted to the swinging jaws and projecting inwardly therefrom, a forming block movable down into the crown of the hat body, a banding ring movable up over the crown on the block, and means for swinging the fingers downwardly and outwardly away from the brim after it is gripped by the jaws. 35

3. In a wet blocking machine, a plurality of brim clamps arranged about the hat body and movable toward and from the body, brim supporting fingers projecting inwardly from the clamps to support the brim prior to being clamped, said fingers being movable downwardly and outwardly from the brim after the brim is clamped, a block movable downwardly into the crown, a banding ring movable upwardly about the crown on the block, and means for projecting water onto the crown to shrink it onto the block. 45

4. A hat blocking machine comprising a series of upright pivoted levers having heads including lower jaws, upwardly reciprocable jaw members above the first jaws and adapted to cooperate therewith to grip a hat brim, brim supporting fingers mounted on said heads and projecting inwardly from the heads to support the brim of a hat body, means for swinging the jaws inwardly to position them on opposite sides of the brim while it is supported on the fingers, means for clamping the reciprocable jaws on the brim, a block movable down into the crown of the gripped hat, a banding ring movable up about the crown on the block, and means for moving the fingers outwardly out of the way of the ring. 55

5. In a hat blocking machine, a plurality of brim clamps arranged about the hat body and comprising upper and lower jaws movable toward and from the hat, the upper jaws being mounted for movement relative to the lower jaws to grip the hat brim, supporting fingers projecting inwardly from the jaws to support the brim of the body, means for moving the jaws in- 60

65

70

75

- wardly to locate them on opposite sides of the brim while it is supported on the fingers, a block movable downwardly into the crown, a banding ring movable upwardly about the crown on the block, and means for moving the fingers outwardly relative to the jaws and out of the way of the ring.
6. A hat blocking machine comprising a plurality of upright levers arranged about a hat body and having heads including clamping jaws, cooperating jaws mounted on the levers and movable to and from the first jaws to clamp a brim between them, said levers being pivoted to permit the jaws to swing toward and from a hat body, brim supporting fingers pivoted to the heads so as to project inwardly from the jaws toward the hat body and swingable downwardly and outwardly away from the brim, means for swinging the jaws inwardly to position them on opposite sides of the brim while it is supported on the fingers, and operating means connected to the fingers to simultaneously swing the fingers downwardly and outwardly away from the brim while it is supported by the jaws.
7. A hat blocking machine comprising a plurality of brim gripping and supporting jaws arranged about an upright center and movable toward and from said center, a block movable downwardly into the crown of a hat body held by said jaws, upright rods mounted for vertical reciprocating movement and located on opposite sides and spaced to the rear of said center, and

a supporting head for the block mounted on said rods and projecting forwardly therefrom so that the center of the block is spaced forwardly of the rods and the space at the front sides of the block is free of obstructions.

8. In a hat blocking machine, a plurality of brim gripping jaws arranged to surround a hat body and movable toward and from the body, a support for a block, a block on said support and movable downwardly into a hat body supported by said jaws, said support including a rigidly mounted horizontal dovetail guide, said block having a similarly shaped laterally extending guide cooperating with that of the support to permit easy removal of the block by sliding movement along the dovetail guide, and means for securing the block on the support.

9. In a hat blocking machine, a plurality of brim gripping jaws arranged to surround a hat body and movable toward and from the body, a block movable downwardly into the crown of a hat body held by said jaws, a banding ring movable upwardly about the crown on said block, means for supporting the ring including a block on which the ring is mounted and having a substantially cross-shaped recess in its lower side, and a vertically reciprocable support having a similarly shaped head to that of the recess and adapted to have the block seated over it to support the block.
